INVENTOR:
PAUL KROUT,
By his Attorneys,

Baldwin & Wright

UNITED STATES PATENT OFFICE.

PAUL KROUT, OF LONDON, ENGLAND.

ILLUMINATED SIGN.

Application filed September 15, 1924. Serial No. 737,760.

To all whom it may concern:

Be it known that I, PAUL KROUT, a subject of the King of Belgium, residing at 61 Wilton Road, London, England, have invented new and useful Improvements in or Relating to Illuminated Signs, of which the following is a specification.

This invention relates to illuminated signs.

10 A sign constructed according to this invention comprises a rotatable member such as a frame or spider having lamps mounted thereon and a translucent screen masking some or all of the lamps, and means are provided for rotating some or all of the lamps on their own axes.

The frame may be located within a stationary case or may, together with one or more translucent screens, constitute a casing or enclosure. In the latter case there may be provided one or more external electric lamps or globes of transparent material which rotate with the frame. The said electric lamps or globes may also if desired be 25 made to rotate upon their own axes. The said internal and/or external electric lamps or globes may be painted or stained in various colour designs, or be provided with coloured glass, so as to change the colours of 30 the visible portions in succession. The said visible portion of the external electric lamps or globes of this apparatus may be enveloped by secondary globes of transparent material or opal glass which may also or 35 alternatively be painted or stained in various colour designs and also show the visible portions in alternate succession. The envelope or secondary globes may remain stationary or may be made to rotate also upon 40 their own axes at a slower or faster speed than the primary electric lamps or globes so as to multiply the variation in colours. The motion of the envelopes or secondary globes may be obtained by the same mechanism 45 which actuates the primary electric lamps or globes. The internal and external electric lamps or globes may be automatically switched on and off simultaneously or alternately by the action of the said internal 50 mechanism or by an external switching device. The timing of the said switching may be varied by adjustment. The whole of the apparatus may be driven by mechanical, electrical or any other means of power.

55 The construction of this sign may be so arranged that the said external electric

lamps or globes are completely or partly covered with translucent material.

Preferably the stationary case comprises a pair of rings cast in one with a pair of inverted U shaped supports which serve to position the rings a distance apart from one another. The rings are provided with a cross member carrying bearings for the rotating frame. Preferably the rings are also divided so that the lower halves can be dropped or turned about a pivot to obtain access to the rotating frame or to replace the frosted screens.

70 The accompanying drawings illustrate apparatus made in accordance with this invention. Figure 1 is a front elevation with one of the screens removed. Figure 2 is a section with parts in elevation. Figure 3 is an end elevation of a modification and Figure 4 is a front elevation of Figure 3, parts being in a different position.

75 Referring more particularly to Figures 1 and 2, *a* is a frame carried by a spider *b* the legs of which radiate from a hub *c* mounted on bearings *d* on a spindle *e* which is carried by a plate *w* secured to cross members *w'* attached to a stationary case *y*. Rotatably mounted on each leg of the spider *b* is a shaft *f* which passes through the frame *a* and carries at its outer end an incandescent lamp *g*. On each shaft *f* is a bevel pinion *h* meshing with another bevel pinion *j* on the spider *b* and *k* is a scroll adapted to engage one of the teeth of the bevel pinions *j* as the frame *a* rotates thereby rotating the bevel pinions *h* a distance corresponding to one tooth. Mounted on two legs of the spider *b* are shafts *l* each of which carries at one end an electric incandescent lamp *m* and at the other end a bevel pinion *n* in mesh with a bevel pinion *o* on a shaft *f* whereby the shafts *l* and lamps *m* rotate as the shafts *f* rotate. The frame *a* is located between two screens *p* of frosted glass mounted in the case *y*, so that the lamps *g* are directly seen by the observer whilst the lamps *m* illuminate the screens *p*. The hub *c* has upon it a worm wheel *q* which is driven by a worm *r*.

100 Electric current is supplied to the lamps through leads *s* which extend from slip rings *t* to which current is supplied through brushes *u* thence to slip rings *v* connected to the lamps.

110 In the modification shown in Figures 6 and 7 the case *y* is formed of a pair of rings

cast in one with a pair of inverted U shaped supports y' which serve to position the rings a distance apart from one another. The rings are divided and hinged at y^2 so that 5 the lower halves carrying the frosted screens can be swung down to obtain access to the rotating frame a or mechanism thereon or to replace the frosted screens p . The cross members w' on which the spindle e 10 is fixed are carried by the upper halves of the rings y .

What I claim is:

- 60 1. A sign comprising a case, a translucent screen mounted therein, a spider located within the case, a frame mounted on the spider, means for rotating the spider, shafts mounted on the spider, means for rotating the shafts about their axes, lamps carried by the shafts and projecting beyond the frame, 15 cross shafts mounted on the spider, means for rotating the cross shafts about their axes and lamps carried by the cross shafts.
2. A sign comprising a case, a translucent screen mounted therein, a spider located 20 within the case, means for rotating the spider, shafts mounted on the spider, lamps carried by the shafts, a bevel pinion on each shaft, bevel pinions on the spider in mesh with the before mentioned pinions, and a 25 stationary scroll in mesh with the pinions on the spider.

3. A sign comprising a case, a translucent screen mounted therein, a spider located within the case, a frame mounted on the spider, means for rotating the spider, shafts 35 mounted on the spider, lamps carried by the shafts and projecting beyond the frame, a bevel pinion on each shaft, bevel pinions on the spider in mesh with the before mentioned pinions, a stationary scroll in mesh 40 with the pinions on the spider, cross shafts mounted on the spider, means for rotating the cross shafts about their axes and lamps carried by the cross shafts.

4. A sign comprising a case, a translucent screen mounted therein, a spider located within the case, a frame mounted on the spider, means for rotating the spider, shafts mounted on the spider, lamps carried by the shafts and projecting beyond the frame, 45 a bevel pinion on each shaft, bevel pinions on the spider in mesh with the before mentioned pinions, a stationary scroll in mesh with the pinions on the spider, cross shafts mounted on the spider, additional bevel pinions on the shafts, bevel pinions on the cross shafts in mesh therewith, and lamps carried by the cross shafts.

In testimony that I claim the foregoing as my invention I have signed my name 50 55 60 this 29th day of August, 1924.

PAUL KROUT.
